UNITED STATES PATENT OFFICE.

JOHN F. O'CONNELL AND CLARENCE E. WHITEMAN, OF LA GRANDE, OREGON.

CIGAR-LIGHTER.

1,091,586.

Specification of Letters Patent. Patented Mar. 31, 1914.

Application filed July 22, 1910. Serial No. 573,314.

To all whom it may concern:

Be it known that we, JOHN F. O'CONNELL and CLARENCE E. WHITEMAN, citizens of the United States, residing at La Grande, in 5 the county of Union and State of Oregon, have invented certain new and useful Improvements in Cigar-Lighters, of which the following is a specification.

The present invention comprehends certain new and useful improvements in a cigar lighting apparatus of that type designed for 10 use in cigar stores and like places.

The object of the invention is to produce an improved device of this character including a lighter or torch which is normally supported in an inoperative position and which may be quickly swung into an operative position when desired for use, so as to be readily accessible and to permit the cigar to be 15 conveniently ignited.

A further object of the invention is to produce a cigar lighting apparatus including a wick in which the lighter wick is positively and automatically ignited by and upon its 20 movement into an operative position, means being provided for protecting the wick when moving into operative position and likewise providing means for extinguishing the lighter wick upon its return to an inoperative 25 position and in engagement with the extinguisher.

With these and other objects in view that will more fully appear as the description proceeds, the invention consists in certain 30 constructions, arrangements and combinations of the parts that will be hereinafter fully described and claimed.

For a full understanding of the invention, reference is to be had to the following description and accompanying drawings, in which:

Figure 1 is a perspective view of the cigar lighting apparatus constructed in accordance with our invention, the front of the 45 base being removed; and Fig. 2 is a vertical longitudinal section thereof, the lighter being shown in dotted lines in an operative position.

Corresponding and like parts are referred 50 to in the following description and indicated in all the views of the accompanying drawings by the same reference characters.

Referring to the drawings, our improved cigar lighting apparatus includes a suitable 55 base 1, that is preferably in the form of a

closed box. The cigar lighter or torch is mounted upon the base and in the present instance consists of a hollow cylindrical vessel 2 that is pivotally supported between a pair of brackets 3 so as to be capable of turning about a transverse horizontal axis. The brackets are secured to and upstand from the central portion of the top of the base. The vessel 2 is designed to contain a supply of gasoline or like liquid fuel, and is 60 equipped with a removable cap 4 to admit of the convenient introduction of the liquid therein. At its upper end the vessel has a longitudinally extending reduced neck 5 in which is fitted a wick 6, the upper end of the 65 wick tube being transversely inclined, as shown.

Fixed on one side of the vessel 2 is a rearwardly projecting rocker arm 7 to the free end of which a link 8 is pivotally connected 70 at one end. This link passes substantially vertically through the top of the base at a point in the rear of the pair of brackets 3. The lower end of the link is pivoted to the rear arm of a lever 9 which is disposed 75 within the base and is fulcrumed at an intermediate point, as indicated at 10, to operate in a vertical longitudinal plane. A tension spring 11 draws the rear arm of the lever downwardly so as to cause the lighter 80 or torch to be held in an inoperative position wherein it is disposed substantially vertically. The push piece 12 is pivotally connected to the forward arm of the lever and passes upwardly through the top of the base 85 and terminates above the same in a suitable head or button. When the push piece is depressed, the lever is rocked against the force of the tension spring 11 and such rocking movement is transmitted to the lighter 90 through the link 8 and the rocker arm 7. The lighter is thus turned upon its pivotal axis and the upper end thereof is swung forwardly and downwardly in order to be readily accessible for use in igniting a cigar. 100

A tubular standard or supporting arm 13 upstands substantially vertically from the top of the base in proximity to the rear end thereof. The upper portion of the supporting arm is deflected substantially horizontally and forwardly, as indicated at 14, and overhangs the base and the upper end of the lighter. Depending from the deflected portion of the supporting arm is an extinguishing cap 15 which covers the upper end of 110

the neck 5 when the lighter is in a normal or vertical position, the cap being suitably cut away at the front or inclined transversely to correspond to the inclined terminal of the wick tube to permit the wick to pass out of and return to the same without injury during the movements of the lighter. By this means the wick is protected from injury during the movements of the wick tube, but the wick tube and extinguisher are brought into close contact on all sides when closed, and thus produces the instantaneous extinguishment of the wick.

At its upper end the supporting arm terminates in a housing or casing 17 which contains a spark plug 16. The body portion of the housing is substantially inverted cup-shape and is formed of suitable metal which is insulated on the inside. The lower end of the body portion is closed by a plate 18 that is fitted therein and is detachably secured thereto by screws or like fastening means. The spark plug 16 is disposed substantially vertically and is carried by this plate and passes downwardly therethrough at a point in front of the extinguishing cap 15. The spark plug is of conventional form and includes separate electrodes 19 that are exposed at the lower end of the spark plug and are spaced apart to provide a gap across which the spark jumps. The electrodes are arranged in the path of the movement of the upper end of the wick so that the wick wipes thereacross during such movement.

Wires 20 are connected to the respective electrodes 19 within the housing and are led through the tubular supporting arm 14 and are connected to an induction spark coil 21 within the base. The spark coil is included in a circuit 22 that may be supplied with current from any suitable source, as for instance a battery composed of a plurality of dry cells 23 which are also contained within the base. The circuit 22 is controlled by a switch consisting of co-acting contact members 24 and 24^a. These members are located at the front portion of the base, the member 24 being relatively stationary while the other member is mounted to swing upon the forward arm of the lever 9. In a normal position of the lever the contact member 24^a is supported above and in spaced relation to the contact member 24 whereby to maintain the circuit 22 open, and when the lever is depressed the swinging contact automatically adapts itself to the stationary contact and engages the same.

In the practical operation of our improved cigar lighting apparatus, the push piece 12 is depressed by the operator and the rocking movement of the lever 9 is effected against the force of the tension spring 11. As before stated, this movement of the lever causes the lighter to be turned about its axis in a direction to swing

the upper end of the lighter forwardly and downwardly. The forward movement of the upper portion of the lighter first moves the neck 5 from beneath the extinguishing cap 15, and then causes the wick 6, which protrudes slightly from the neck, to wipe momentarily across the electrodes 19. By the time that the wick reaches the spark plug, the lever 9 has been rocked sufficiently to engage the contact members 24 and 24^a to close the circuit 22, whereby to pass the current through the spark coil 21 and to effect an electrical discharge between the electrodes 19. The sparks jumping across the gap between the electrodes ignite the wick 6 so that the lighter is ready for immediate use. The turning movement of the lighter continues until the neck has been swung forwardly and downwardly past the spark plug to assume the operative position illustrated in dotted lines in Fig. 2, wherein the flame of the lighter is conveniently accessible for use in igniting cigars or the like. When the push piece 12 is relieved of pressure the parts are returned to their normal positions through the instrumentality of the tension spring 11, the contact members 24^a being disengaged from the other contact member to again open the circuit 22 and prevent further electrical discharge between the electrodes 19. The lighter is, of course, swung to its upright or inoperative position, the upper end of the neck passing under the extinguishing cap 15 and being inclosed thereby so as to smother the flame and insure against the waste of fuel when the lighting apparatus is not desired for use.

The induction coil 21 has a suitable interrupter 25, so as to cause a continuous discharge of sparks between the electrodes 19 while the circuit 22 is closed.

Attention is particularly directed to the fact that both the circuit 22 and the circuit through the wires 20, are independent of the lighter. Such an arrangement insures a positive and reliable operation of the device.

Having thus described the invention, what we claim is:

A cigar lighter including a base, an electrical igniting device supported thereon, a pivotally mounted fuel vessel carrying a wick, the circuit through the igniting device being normally broken and the fuel vessel being normally in inoperative position, and means for simultaneously swinging the fuel vessel into operative position and completing the circuit through the igniting device, said means including a centrally pivoted lever carried by the base, a crank arm connected to the fuel vessel, a pivoted link connecting the crank arm and one terminal of the lever, a spring connected to the lever, whereby the fuel vessel is normally held in inoperative position, a contact member carried by one terminal of the lever and normally held in

open circuit position by the said spring, and
a push rod secured to the contact carrying
terminal of the lever, whereby the last men-
tioned terminal of the lever may be de-
5 pressed against the tension of the said spring
to move the said contact into closed circuit
position and to swing the fuel vessel into
operative position.

In testimony whereof, we affix our signa-
tures in presence of two witnesses.
